NELSON L. HUFF, OF MILFORD, MASSACHUSETTS

REAMER

Application filed November 22, 1927. Serial No. 235,952.

The present invention relates to cutting implements, commonly known as reamers, employed for finishing bearing and similar cylindrical surfaces. The object of the present invention is to provide a new and efficient type of reamer which is effective for cutting a bearing surface, and which within limitations may be adjusted to ream or finish holes of varying dimensions.

With this and other objects in view, the various features of the invention consist in certain novel features of construction, combinations and arrangements of parts, herein-after described and claimed, the advantages of which will be obvious to those skilled in the art from the following description.

In the accompanying drawings illustrating the preferred form of the invention,

Fig. 1 represents a top plan view of the improved reamer;

Fig. 2 is a side elevation of the reamer shown in Fig. 1;

Fig. 3 is a longitudinal section in elevation; and

Fig. 4 is a cross-section of the reamer upon the line B—B of Fig. 2.

As indicated more particularly in the drawings, the reamer comprises essentially a steel bar 1 having a cutting portion 10 and a shank portion 12 provided with a squared end 14 for the reception of an operating instrumentality. The cutting portion is provided with cutting edges 15 and 16 designed to engage and ream the interior of a cylindrical opening when the reamer is rotated therein. Cooperating with the cutting portion of the reamer for the purpose of maintaining the cutting edges in uniform cutting relation to the opening is a partially cylindrical shoe 2, which, as indicated in the drawings, is mounted upon the steel bar opposite the cutting edges 15 and 16. This shoe is intended to maintain the cutting edges in true contact with the surface of the opening on rotation of the reamer, and facilitate the rotation within the opening. The present construction is so designed that by proper adjustment, the cylindrical surface of the shoe may be caused to approach or recede from the cutting edges and within limits vary the effective diameter

of the reamer, and in consequence adjust it for operating within openings or bearings of varying dimensions. To this end the surface of the bar 1 opposite the cutting edges is gradually tapered, as indicated at 6, this 55 tapered surface engaging a similarly tapered surface 18 formed upon the shoe 2. As indicated more particularly in Fig. 4, the partial cylindrical shoe is provided with a longitudinally inclined slot which causes the cylindrical surface of the shoe to extend parallel to the cutting edges in any adjusted position thereof. The shoe 2 is conveniently adjusted through the provision of a threaded stem 3 mounted in the shoe and extending 60 from one end, the stem projecting loosely through an opening formed in the upturned end 5 of the bar 1. The stem is located in adjusted position with relation to the upturned end 5 by lock nuts 4 engaging with the stem 65 upon opposite sides of the end, as will be clearly evident from the drawings. It will be evident that, owing to the provision of the adjustable shoe 2, the reamer may be adapted for finishing bearings or similar 70 openings of varying dimensions within close limits, and that furthermore by substituting shoes having different diameters, the reamer may be adapted for openings having a considerable variation. For example, it has been 75 found that with the type of reamer shown in the drawings, by substituting different shoes and by proper adjustment, a single reamer bar may be effectively employed for finishing openings varying from $\frac{1}{8}$ to $\frac{15}{16}$ inch 80 in diameter. It will be evident that the adjustable shoe 2, as shown in the drawings, is preferably made of wood. This is desirable 85 as the wooden shoes may be easily made and replaced, and furthermore this type of shoe facilitates the rotation of the reamer within the opening. It will be understood, however, that the shoe may be made of any suitable 90 material, and that the invention is not limited in its scope to the type of shoe illustrated 95 in the drawing.

What is claimed is:

1. A reamer comprising an elongated bar having four surfaces providing a generally rectangular cross-section of the bar, cutting 100

edges formed on one surface of the bar within the cutting region, the surface of the bar opposite the cutting surface being provided with a gradual taper, and a cylindrical guide shoe extending throughout the major portion of the tapered surface, having a similarly inclined longitudinal slot for engagement with the tapered surface of the bar, the guide shoe completely surrounding the tapered surface
5 and the major portion of the two side surfaces but allowing the cutting edges to protrude, whereby longitudinal adjustment of the guide shoe with relation to the cutting bar increases or diminishes the effective diameter of the reamer without alteration of its cylindrical characteristics.

2. A reamer comprising an elongated bar having four surfaces providing a generally rectangular cross-section of the bar, cutting
20 edges formed on one surface of the bar within the cutting region, the surface of the bar opposite the cutting surface being provided with a gradual taper, a cylindrical and non-metallic guide shoe extending throughout the
25 major portion of the tapered surface having a similarly inclined longitudinal slot for engagement with the tapered surface of the bar, the guide shoe completely surrounding the tapered surface and the major portion
30 of the two side surfaces but allowing the cutting edges to protrude, and means at the cutting end of the bar for adjusting the guide shoe longitudinally thereof, whereby longitudinal adjustment of the
35 guide shoe with relation to the cutting bar increases or diminishes the effective diameter of the reamer without alteration of its cylindrical characteristics.
